UNITED STATES PATENT OFFICE.

AMÉDÉE TREMBLAY, OF ARCADIA, OREGON.

RAIL-JOINT.

SPECIFICATION forming part of Letters Patent No. 633,926, dated September 26, 1899.

Application filed May 10, 1899. Serial No. 716,242. (No model.)

To all whom it may concern:

Be it known that I, AMÉDÉE TREMBLAY, a citizen of the United States of America, residing at Arcadia, county of Malheur, State of Oregon, have invented certain new and useful Improvements in Rail-Joints; and I do hereby declare that the following is a full, clear, and exact description of the invention, such as will enable others skilled in the art to which it appertains to make and use the same.

This invention relates to rail-joints, and has for its object to provide a device of this character which is simple in construction, of few parts, and which is strong and reliable in operation.

To these ends the invention consists in a rail-joint constructed substantially as hereinafter illustrated and described, and defined in the appended claims.

Referring to the drawings, in which similar letters of reference indicate similar parts, Figure 1 is a view in perspective of a rail-joint constructed in accordance with this invention. Fig. 2 is a vertical transverse section on the line 2 2 of Fig. 1. Fig. 3 is a similar section on the line 3 3 of Fig. 1. Fig. 4 is a view in perspective of the end of one of the rails separated from the other rail. Fig. 5 is a similar view of the other rail.

In the drawings, A and A' represent the meeting ends of two rails, which may be of the usual or any preferred construction. The flange of the rail A is somewhat thickened at its end and is cut away or recessed, forming the shoulder or stop a and the extension a' , while the body and head of the rail are similarly cut away, forming the vertical flange a^2 . A groove a^3 is formed in the edges of the flange and the under side of the extension a' of the rail A adjacent to the shoulders a . At the outer end of the extension a' are secured two staples a^4 , one on each side of the vertical flange a^2 . The flange of the rail A' is also thickened and cut away similarly to the rail A, forming a stop or shoulder b and an extension b' . The extensions a' and b' are adapted to overlap, and their ends abut, respectively, against the shoulders a and b . The end of the rail A' is centrally slotted, as at b^2 , to provide a seat for the vertical flange a^2 of the rail A. The sides of the extension b' of the rail B are

provided near the front end thereof with notches b^3 , which are in alignment with the groove a^3 of the extension a' when the said extensions are in their overlapped or operative position. The rear end of the extension b' is also provided with recesses b^4 , which are adapted to receive the staples a^4 .

A yoke-shaped spring-clip D, having hooks d at the extremities thereof, is adapted to be seated within the groove a^3 of the extension a' , the arms d' thereof engaging the notches b^3 of the extension b' , while the hooks d bear upon the top of the extension b' , serving to bind the two rails together, as shown in Fig. 1.

The staples a^4 are adapted to engage the recesses b^4 when the extensions a' and b' are in their overlapped position, and a wedge E is driven through the upper end thereof to tightly secure the parts in position.

If desired, a pin (not shown) may be driven in the upper portion of the wedges E back of the staples to prevent the accidental loosening thereof.

While I have herein shown a preferred form of carrying my invention into effect, yet I do not desire to limit myself to such preferred details of construction, but claim the right to use any and all modifications thereof which will serve to carry into effect the objects to be attained by this invention in so far as such modifications and changes may fall within the spirit and scope of my said invention.

I claim—

1. In a rail-joint, the combination with a rail having its end cut away forming a vertical flange, a stop at the inner end of said flange, of a rail having its end slotted to receive said vertical flange and a spring-clamp adapted to embrace the meeting ends of said rails for locking the rails together, substantially as described.

2. In a rail-joint, the combination with a rail having its end cut away forming a vertical and a horizontal flange, a stop arranged at the inner end of said flanges, a groove formed in the edges and under side of said horizontal flange, and a staple at the outer end of said horizontal flange, of a rail having its end slotted to receive said vertical flange and recessed upon the under surface to receive the said horizontal flange, notches

95 100

formed in the under side of the slotted portion adapted to coincide with the said grooves in the edge of the said horizontal flange, recesses formed in said slotted portion adapted 5 to receive the said staples, and wedges adapted to be inserted in the upper ends of said staples, substantially as described.

In witness whereof I have hereunto set my hand in the presence of two witnesses.

AMÉDÉE TREMBLAY.
